UNITED STATES PATENT OFFICE

JAMES C. OLSEN, JR., HARRY L. BOTTLE, AND FRANK W. JOHNS, OF ANDERSON, INDIANA

STOVE

Application filed June 30, 1930. Serial No. 464,762.

Our invention relates to the manufacture of stoves, and in general its object is to construct new means for attaching the legs to the bottom of a stove and for attaching the base-strips to the legs, whereby among other advantages the assembly and disassembly of these parts is facilitated, the leg support of the stove is independent of the base-strips, and the leg-brackets to which the base-strips are bolted are provided with cored holes for the bolts.

One feature of our invention consists in providing at the corners of the stove dove-tail joints between the stove-bottom and legs consisting of tenons on the legs to seat in and interlock with mortises in the stove-bottom, and providing the leg-tops and the stove-bottom with bolt-holes arranged to register when these parts are assembled to receive attaching bolts.

Another feature of our invention consists in providing the legs and base-strips with inwardly extending brackets having bolt-holes arranged to register when these parts are assembled to receive attaching bolts, and also having interengaging devices constructed to interlock when the parts are drawn together by their bolts.

Another feature of our invention consists in a core tin designed to form a cored hole in the cast leg-bracket at an angle of 45 degrees more or less to the vertical draw of the pattern.

Other improvements and advantages will appear from the accompanying detailed disclosure of our invention.

In the accompanying drawings which illustrate practical embodiments of our improvements,

Figure 1 is a detail view in elevation of the assembled stove-bottom, leg and base-strips, these parts being broken away;

Figure 2 is a bottom plan view of parts shown in Figure 1;

Figure 3 is a sectional view on the line 3—3 in Figure 2;

Figure 4 is a sectional view on the line 4—4 in Figure 3 with the bolt and nut omitted;

Figure 5 is a perspective side view of one of the core tins for the leg brackets;

Figure 6 is an end view of the same with its sleeve rammed with core sand, and

Figure 7 is a sectional view on the line 7—7 in Figure 6 with the sleeve and chamber rammed with core sand.

In the drawings the reference letter 10 represents a corner section of the bottom angle-iron frame of a stove having its vertical web or flange 11 and its horizontal internal rib 12 continuous around each of its corners. The web 11 is provided with vertical mortises 13 on opposite sides of each corner, being offset inwardly to provide increased strength at each mortise as shown at 14; the ribs 12 at each corner are inwardly extended to form a horizontal corner shelf 15 which is provided with a bolt hole 16 inside the webs to receive a screw-threaded bolt 17, the underside of the shelf preferably being countersunk around the hole to provide an angular seat for a retaining nut (not shown) to hold the bolt-head down on the shelf. Each leg has angular side walls or wings 18 which are provided at their upper ends with tenons 19 constructed to enter and seat in the mortises 13 when the parts are assembled, and each leg has at its upper end an inwardly projecting lug 20 in the angle of its walls constructed to rest against an associated shelf 15 and having a bolt-hole 21 in line with its hole 16 to receive the bolt, a wing nut 22 being employed to hold the parts in assembly. In practice the mortises in the stove-bottom are undercut and downwardly and outwardly flared or inclined, and the tenons on the leg-tops are correspondingly splayed and beveled to conform to the mortises so that the parts can be readily assembled by seating the stove-bottom on the legs.

Each of the base strips 23 extending between the legs below the frame 10 is provided at its ends with an inset angular bracket 24 fitting the contour of a leg-wing 18 and having a forked or bifurcated head 25 to receive and seat the head-end of a screw threaded bolt 26. Each leg-wing has an angular metallic bracket cast with it and consisting of a spaced pair of parallel inwardly directed horizontal ribs or flanges 27 inclined or beveled from their inner ends toward

their outer ends and there formed with straight faces 28 at right angles to the leg wing to abut against the head 25, and a vertical cross-web 29 at the outer ends of the flanges 27 provided with a bolt-hole in line with the forked seat in the head 25, so that when the nut 30 on the bolt 26 is drawn against the shelf the base strips are fastened to the legs. The ends of the heads 25 are formed with horizontal lateral extensions 25' which form seats for the leg-brackets and support the base-strips in position on the legs and against the frame, these parts being arranged so that when the nuts 30 are turned down the base-strips are flush with the frame and leg-wings. The bolt-heads point away from the legs to afford ample room for the assembler to seat a screw driver in them and turn them to rotate the bolts and draw the parts together, the nuts being held against rotation during assembly or disassembly of the parts by any suitable means and preferably by the flanges of the brackets. In practice we prefer to make the bolt-holes in the leg brackets in the mold when the leg is cast, and for this purpose we provide a core tin made from a suitable metal blank bent to form a rectangular base 31, triangular wings 32, inner end wall 33, bridge 34 and outer wall 35; the wings and wall 33 have attaching clips 36 and 37 respectively constructed to be bent as shown to hold these parts in erected position, and a sleeve 38 is supported in the walls 33 and 35 to form a cored bolt-hole in the cross-web 29 of the bracket. The walls 33 and 35 are inclined or beveled inwardly from the bridge 34 toward their ends, and the bridge extends slightly beyond the wall 33, as shown in Figs. 5 and 6. After the core-tin is thus formed a mixture of black sand and binder material is rammed into the space between the wings and into the sleeve as indicated at α , so that the device then provides a core-box, and a pair of them are oppositely seated in a V-shaped pattern formed with recesses to receive their bases 31 and the free ends of their walls 35 and with the core-boxes inclined to each other and the faces of the rammed material α opposite each other; the pattern and its core-boxes are seated in the mold-drag in position with relation to the leg-pattern and the drag is rammed with sand, the pattern carrying the core-boxes having triangular wings outside the wings 32 to form matrices in the sand for the metal forming the flanges 27. As the core boxes are at an angle to each other having its apex toward the open side of the drag, and the wings 32 and walls 35 are inclined upwardly when the pattern is removed from the drag it can be lifted and stripped from the boxes without disturbing them and they will remain in place in the sand. When the metal is poured to form the leg it forms the side ribs 27 of the brackets adjacent the wings.

32 and the cross-webs 29 of the brackets in the spaces between the walls 33 and 35 and around the sleeves 38, all integral with the leg, and after the metal cools the rammed material α is removed. We thus form a cored hole in each bracket when the leg is cast and eliminate the necessity of boring these bolt-holes in the machine shop. The extended ends of the bridge 34 beyond the wings 32 form sharp corners on the ribs 27 and prevent formation of fins or burrs on the casting.

When the parts are assembled the attaching bolts and their co-operating parts are all concealed, and when the usual sheet metal or iron body of the stove is positioned on the frame it covers the dovetail connections between the stove-bottom and its legs.

We claim:

1. In a stove the combination of a bottom frame having vertical and horizontal portions around its corner, the latter portions forming an integral corner shelf and the former portions having downwardly flared cross mortises on opposite sides of the corner, a leg having tenons constructed to seat in said mortises and an inwardly projecting lug below said shelf, and means to clamp the shelf on the lug.

2. In a stove, a leg having angular side walls provided with upwardly directed tenons and an inwardly extending lug between the latter, a stove-bottom having downwardly flared mortises on opposite sides of its corner to receive said tenons, a corner shelf between said mortises and resting on said lug, said lug and shelf having alined bolt-holes, and bolts securing said parts together.

3. In a stove the combination of a frame and corner legs, base-strips extending between the legs below the frame, interengaging brackets on the rear faces of the strips and legs constructed to interlock and support the strips when they are assembled in position on the legs, and means clamping said brackets together.

4. In a stove the combination of a frame and angular corner legs, base-strips extending between the legs below the frame, interengaging brackets integral with the strips and legs and constructed to support the strips when they are assembled in position on the legs, each leg bracket having a cored bolt-hole and each strip bracket having a bolt-seat alined with a bolt-hole, and screw bolts clamping said brackets together.

5. In a stove, a metallic leg having angular side walls provided on their inner faces with integral brackets each consisting of a spaced pair of horizontal flanges and a cross-web, and a core tin composed of a base between the bottom of said flanges, wings adjacent said flanges, spaced walls on opposite sides of said cross-web, and a sleeve between said walls and forming a cored bolt-hole in said cross-web.

6. In a stove, a metallic leg having angular side walls provided on their inner faces with integral brackets each consisting of a spaced pair of horizontal flanges and a cross-web, and a core tin composed of a base between the bottoms of said flanges, wings adjacent said flanges, spaced walls on opposite sides of said cross-web, and a sleeve between said walls and forming a cored bolt-hole in said cross-web, said wings being beveled upwardly and outwardly from their inner ends away from the angle of said side walls.

7. In a stove, a core tin providing a cored hole in the web of a metallic bracket cast integral with a stove leg and consisting of a rectangular base, an inner wall at an angle to said base, triangular wings connecting said wall and base, an outer wall spaced from and parallel with said inner wall, a bridge connecting said walls at their outer ends, and a sleeve carried by said walls intermediate their ends, said walls being beveled inwardly from their outer ends toward their inner ends.

25 In testimony whereof we affix our signatures.

JAMES C. OLSEN, JR.
